UNITED STATES PATENT OFFICE.

ALICE M. RICHARDS, OF OSHKOSH, WISCONSIN.

VASE HOLDER.

Application filed January 25, 1926. Serial No. 83,656.

My invention relates to vase holders of the collapsible frame type, such as shown in my prior Patent 1,559,005, for supporting in a stable manner collapsible paper vases such as shown in my prior Patent 1,490,026, my present purpose being to provide a wall vase holder, that is, one that is adapted to be hung against a wall or similar support and which may be folded to operative and inoperative positions, in the former position affording a firm and staunch support for a vase positioned therein, and in the latter position being inconspicuous and out of the way.

It is also my purpose to provide a wall vase holder that is neat and attractive in appearance, strong, durable, cheap and easy to produce and thoroughly reliable and efficient in use.

With the foregoing and other purposes in view, my invention consists in the novel features of construction, combination and arrangement of parts as will be hereinafter more fully described, illustrated in the accompanying drawings and defined in the appended claims.

In the drawings, wherein like characters of reference denotes corresponding parts in the different views:

Fig. 1 is a front elevation of a wall vase holder constructed in accordance with my invention, showing the same in a folded or collapsed condition;

Fig. 2, a side elevation showing my vase holder in an operative or set up condition with a vase positioned therein; and

Fig. 3, a top plan view of my vase holder in its set up condition.

As shown in the drawings my improved vase holder preferably is formed from flat metallic strips and consists essentially of only three main parts, namely, a frame 10 and upper and lower ring elements 12 and 14, respectively, which latter are pivoted to said frame for swinging movement between inoperative or collapsed and operative or set up positions as shown, respectively, in Figures 1 and 2.

Frame 10 is formed from a single strip of material bent upon itself substantially midway between its ends to provide an eye 16 by means of which said frame may be suspended from a nail or the like projecting from a wall or similar support, and from said eye the two side arms, 18, 20, respectively, of said frame are extended down-

wardly in side to side abutting relation for a considerable distance and then diverged outwardly as at 22, 24, respectively, after which they are converged as at 26, 28, respectively, and their lower end portions 30, 32 brought relatively close together in spaced parallelism with the extreme free end portion 34 of one of said arms, arm 18 in this instance, bent to extend laterally across the space between said portions 30, 32 and to underlie the free end of the other portion, portion 32 in this instance.

Upper ring element 12 which may be of any desired shape, being shown of octagonal outline in this instance, is formed from a single strip of material and has its free end portions 34, 36 extended for a limited distance in spaced parallelism and engaging, respectively, the outer faces of arms 18, 20 of frame 10, a pin or rivet 38 being passed through aligned openings in said arms 18, 20 and in the free ends of portions 34, 36 to pivotally connect ring element 12 to frame 10 for swinging movement between the positions shown in Figs. 1 and 2. In the inoperative position of ring 12 shown in Fig. 1, that is, when said ring is swung to a vertical position in the plane of frame 10, portions 34, 36 frictionally engage arms 18, 20 and thus serve to hold said ring in such position, while on the other hand, when ring 12 is swung to a horizontal or operative position as shown in Fig. 2, the lower edges of portions 34, 36 contact with the diverging portions 22, 24, respectively, of frame 10 whereby said ring is held in its latter position.

Lower ring 14 also is formed from a single strip of material and has its free end portions 40, 42 extended in side to side abutting relation and received between the portions 30, 32, of frame 10, a pin or rivet 44 serving to pivotally connect said portions 40, 42 with said portions 30, 32 whereby ring 14 may be swung between its inoperative and operative positions shown, respectively, in Figures 1 and 2, in the former position lying in the plane of frame 10 between the portions 26 and 28 thereof, and being so held by reason of the frictional engagement of portions 40, 42 with portions 30, 32, and in the latter position extending horizontally from frame 10 and being held in such position by reason of the lower edges of portions 30, 32 contacting with the horizontal portion 34 of frame 10.

Portions 40, 42 of ring 14 are of such length that when both rings 12 and 14 are swung to horizontal positions the center of ring 14, which latter preferably is of more or less elliptical shape thereby to better hold a collapsible vase in set up condition, is in vertical alinement with the center of ring 12, so that a vase, illustrated at 46 by dotted lines in Fig. 2, will be supported in upright position when placed as shown within said rings, and will be firmly supported by said holder as is obvious. When the holder is not in use the rings 12, 14 are swung to their out of the way positions shown in Fig. 1.

From the foregoing description considered in connection with the accompanying drawings, it is believed that the construction, operation and advantages of my improved vase holder will be fully understood. I desire to point out, however, that various changes and desirable additions may be made in and to the same within the spirit and scope of my invention as defined in the appended claims.

I claim:

1. A vase holder comprising a frame including a portion having an eye at the upper end thereof whereby the holder may be suspended from a support projecting from a wall, portions of said frame being extended laterally from said first mentioned portion for engagement with a wall to prevent the frame from rotating upon a support by which it is suspended, and a vase receiving ring including a pair of arms embracing the first mentioned portion of said frame and pivoted to the latter to permit the ring to be swung between a position at an angle to said frame and a position in the

plane of said frame, the pivot of said ring being located adjacent to the laterally extending portions of said frame whereby said laterally extending portions constitute stops to limit swinging movement of said ring beyond a predetermined angular relation with respect to said frame.

2. A vase holder comprising a frame including a pair of side arms extending for a portion of their length in spaced parallelism, a member extending across the space between said parallel portions, and a pair of ring members pivoted to said frame for swinging movement to and from positions in spaced parallelism to positions in alinement in the plane of said frame, one of said ring members being pivoted to said frame between the parallel portions thereof adjacent to said cross member whereby the latter serves as a stop to limit swinging movement of said ring member.

3. A vase holder comprising a frame including a pair of side arms extending for a portion of their length in parallelism, the parallel portion of one of said arms terminating in a right-angular extension, and a pair of vase receiving ring members pivoted to said frame for swinging movement between positions in spaced parallelism and positions in alinement in the plane of said frame, one of said ring members being pivoted to said frame adjacent to said right angularly extending terminal portion thereof whereby the latter serves as a stop to limit swinging movement of said ring member.

In testimony whereof I hereunto affix my signature.

ALICE M. RICHARDS.
